27 Jakob Podien Inventor

UNITED STATES PATENT OFFICE.

JAKOB PODIEN, OF CHICAGO, ILLINOIS.

CAR-REPLACER.

1,351,965.

Specification of Letters Patent.

Patented Sept. 7, 1920.

Application filed July 9, 1919. Serial No. 309,748.

To all whom it may concern:

Be it known that I, JAKOB PODIEN, a citizen of the United States, residing at Chicago, in the county of Cook and State of Illinois, have invented certain new and useful Improvements in Car-Replacers, of which the following is a specification.

This invention relates to a guide for replacing de-railed railway rolling stock, and 10 an object of the invention is to provide a pair of castings and means for attaching them to the rails of a railway track, for re-railing rolling stock in case it becomes de-railed or jumps the track which members 15 may be carried as a part of the equipment of the locomotive and attached to the track in front of the latter when necessary. A further object of the invention is to provide an inner and an outer member or casting 20 which are adapted for positioning upon the inner and outer sides of the rail of a railway track for guiding the flanges on the wheels of the rolling stock into proper engagement with the inner sides of the T-rails 25 of the track.

A further object of the invention is to provide a novel form of attaching means whereby the said castings or members may be quickly and easily attached to or detached 30 from the railway tracks.

Other objects of the invention will appear in the following detailed description taken in connection with the accompanying drawings forming a part of this specification and 35 in which drawings:

Figure 1 is a plan view of the re-railing structure.

Fig. 2 is a side elevation of the rolling stock replacing structure being applied.

40 Fig. 3 is a section on the line 3-3 of Fig. 1.

Fig. 4 is a section on the line 4-4 of Fig. 1, and

45 Fig. 5 is a detail perspective view of the section for leading the wheel flanges over the rail, for engagement with the inner edge of the ball thereof.

Referring more particularly to the drawings, wherein like characters indicate like 50 and corresponding parts throughout the several views, A indicates one rail of the railway track, while the other rail is indicated by B. As is ordinary in the construction of railway tracks, these rails A and B are supported by the usual ties C. The re-railing or replacing structure comprises an inner

member 10 and an outer member 11 which are attached respectively at the inner side of one rail and the outer side of the other rail, as clearly shown in Fig. 1 of the 60 drawings.

The inner member or section 10 comprises a relatively large body having laterally extending longitudinal flanges 12 upon its inner lower edge, which are provided with a 65 plurality of notches 14 adapted to receive therein spikes as indicated at 15 for securely attaching the member 10 to spaced ties C. The flanges 12 terminate at spaced distances from the transverse center of the body or 70 casting 10 and a chair 16 is formed upon the body intermediate the ends of the flanges 12. This chair 16 projects beneath the base of the rail A, and projects upon the opposite side of the base from that upon which 75 the body 10 is mounted. The chair 16 is provided with an opening 17 near its outer end which receives therethrough a wedge 18, adapted for wedging engagement against the outer edge of the base of the rail A, 80 securely clamping the body 10 to the rail and positioning the inner portion of the base of the rail A within the recesses 19 formed in the body 10 as clearly shown in Fig. 3 of the drawings. The body 10 has a lateral 85 projection 20 thereon which fits against the inner side of the web of the rail and against the under side of the inner portion of the ball of the rail, providing a snug fitting engagement between the body or member 10 90 and the rail A.

The lateral extension 20 extends throughout only a part of the length of the casting or body 10, at the intermediate portion thereof, and the inner side of the casting 95 for the major portion of its length inclines toward the web of the rail from its uppermost portion which is spaced from the rail. The body 10 is provided with opposed leads 21 inclining upwardly toward the transverse 100 center of the body from each end thereof, and bordered upon either side by upstanding flanges 22 at their inner edges and 23 at their outer edges. These leadways converge at the transverse center of the body and 105 gradually decrease in width as they increase in height. The flanges 22 terminate intermediate the transverse center of the body 10 providing an opening or space 24 to permit the flanges on the wheels of the rolling stock 110 which is being replaced upon the track to pass off of the leads upon the extension 20

while the peripheries of the wheels engage the balls of the rail A, thus properly positioning the wheels at this or the corresponding side of the rolling stock. The wheels of 5 the opposite sides of the rolling stock are replaced by means of the structure 11.

The structure 11 comprises a main body casting having laterally extending longitudinal flanges 30 along its outer lower edges 10 which terminate at spaced distances from the transverse center of the body and are provided with a plurality of notches 31 any one of which in each flange is adapted to receive a spike 32 such as ordinarily used for fastening the T-rails to the ties of a railway track, for securely attaching the casting 11 to spaced ties C and preferably the same ties to which the casting 10 is attached. The portions of the outer sides of the casting or body 11 intermediate the inner ends 20 of the flanges 30 is flat and has a rib 33 formed thereon intermediate its edges. This rib engages in a recess 34 formed in a clamping wedge 35. The clamping wedge 35 extends through an opening in the vertical portion 36 of the attaching chair 37, and is provided with a plurality of spaced openings 38 extending transversely therethrough at different distances from its ends 25 as clearly shown in Fig. 4 of the drawings, any one of which openings is adapted to receive a pin 39 which is adapted to engage against the inner sides of the vertical portion 36 of the chair 37 for securely clamping the wedge clamp 35 in position and in engagement with the outer side of the intermediate portion of the body 11. The pin 40 extends transversely through the outer end of the clamping wedge 35 and is held 30 against accidental movement out of its receiving opening by a cotter pin 41, to which the pin 39 is connected by a flexible member or chain 42.

The chair 37 extends beneath the body 11 45 and the base of the rail B, having an overhanging portion 42 formed upon its end opposite to the end upon which the vertical portion 36 is formed, which overhanging portion forms, with the main body of the chair 37 a recess 43 for receiving therein the inner portion of the base of the rail B as 50 clearly shown in Fig. 4 of the drawings.

The body or casting 11 is provided with opposed leads 44 and 45 leading upwardly 55 from its outer end, and gradually inclining as they extend toward the transverse center of the body. The lower outer edges of the leads 44 and 45 are substantially flush with the upper surface of the ties C so that 60 the sleeves will pick up the wheels of the derailed rolling stock for leading them upwardly and replacing them upon the rail B. The leads 44 and 45 are bordered on their 65 inner edges by upstanding flanges 46 and on their outer edges by upstanding flanges

47. These leads 44 and 45 like the leads 21 converge laterally as they extend upwardly providing constricted portions opening out through the space 48 formed at the spaced ends of the upstanding flanges 46. The 70 body 11 is enlarged laterally at its inner side intermediate its ends, providing the enlargements 49. The inner ends of the flanges 46 are enlarged, as clearly shown at 75 50, and their inner edges are angled for alinement with the outer angled edges 51 of the flange guide ways 52, formed in the section 53 of the re-railer or replacer. The section 53 has depending lugs 54 upon its inner edge which engage the end of the enlargement 49 to prevent longitudinal displacement of the section 53 which rests upon the upper surface of the ball of the rail B and is provided for guiding the flanges of the wheels of the rolling stock over the rail 80 85 B for proper engagement with the inner surface of the ball thereof. The end portions of the upper surface of the member or section 53 are beveled and inclined downwardly toward the terminals of the said 90 members or sections as shown at 55 in the drawings, to permit the easy riding of the peripheries of the wheels of the rolling stock thereover for engagement upon the upper surface of the ball of the rail B. 95

Changes in details may be made without departing from the spirit of this invention, but;

I claim:

1. In a re-railer, the combination with 100 rails and ties of a railroad, of a pair of members, means for attaching one of said members at the inner side of a rail, means for attaching the other of said members to the outer side of a rail, detachable means 105 overlying the ball of the rail and associated with said last named member for guiding a wheel and flange across the rail to which the member is attached, and means for securing the members to the railroad ties. 110

2. In a re-railer, the combination, of a pair of members, means for attaching one of said members at the inner side of a rail, means for attaching the other of said members to the outer side of a rail, upwardly 115 extending lead ways formed upon said members and converging at their upper ends and at the transverse centers of the members, upstanding flanges along the sides of said leadways, the flanges adjacent the rails to 120 which the members are attached, terminating short of the transverse centers of the members, and detachable means associated with said second mentioned member for guiding a wheel and flange across the rail 125 to which the second mentioned member is attached.

3. In a re-railer, the combination with a rail, of a member comprising a relatively large body provided with a pair of lead- 130

- ways extending from each end thereof, toward its transverse center, said leadways gradually decreasing in width as they extend to the transverse center of the body, 5 upstanding flanges formed along the sides of said leadways, the flanges at one side of the leadway terminating short of the transverse center of the body, and means for detachably connecting said member to the base 10 of a rail,
4. In a re-railer, the combination, of a member comprising a relatively large body provided with a pair of leadways extending from each end thereof, toward its transverse 15 center, said leadways gradually decreasing in width as they extend to the transverse center of the body, upstanding flanges formed along the sides of said leadways, the flanges at one side of the leadway terminat- 20 ing short of the transverse center of the body, a laterally extending enlargement formed upon one side of said body intermediate its ends and adapted to be positioned adjacent a railway rail to which the body is 25 attached.
5. In a re-railer, the combination, of a member comprising a relatively large body provided with a pair of leadways extending from each end thereof toward its transverse 30 center, said leadways gradually decreasing in width as they extend to the transverse center of the body, upstanding flanges formed along the sides of said leadways, the flanges at one side of the leadway terminat- 35 ing short of the transverse center of the body, a laterally extending enlargement formed upon one side of said body intermediate its ends and adapted to be positioned adjacent a railway rail to which the body is 40 attached, a removable member adapted for co-action with said body for resting upon the ball of the railway rail, said removable member provided with ways having communication with said leads to guide a wheel 45 and its flange across the rail.
6. In a re-railer, the combination, of a member comprising a relatively large body provided with a pair of leadways extending from each end thereof toward the transverse 50 center, said leadways gradually decreasing in width as they extend to the transverse center of the body, upstanding flanges formed along the sides of said leadways, the flanges at one side of the leadway terminat- 55 ing short of the transverse center of the body, a laterally extending enlargement
- formed upon one side of said body intermediate its ends and adapted to be positioned adjacent a railway rail to which the body is 60 attached, a removable member adapted for co-action with said body for resting upon the ball of the railway rail, said removable member provided with ways having communication with said leads to guide a wheel and its flange across the rail, lateral lugs 65 upon said removable members engaging the ends of said laterally extending enlargements to prevent longitudinal movement of the removable members.
7. In a re-railer, the combination, of a member comprising a relatively large body provided with a pair of leadways extending from each end thereof toward the transverse 70 center of the body, upstanding flanges formed along the sides of said leadways, the flanges at one side of the leadway terminating short of the transverse center of the body, a laterally extending enlargement 75 formed upon one side of said body intermediate its ends and adapted to be positioned adjacent a railway rail to which the body is 80 attached, a removable member adapted for co-action with said body for resting upon the ball of the railway rail, said removable member provided with ways having communication with said leads to guide a wheel and its flange across the rail, lateral lugs upon said removable 85 members engaging the ends of said laterally extending enlargements to prevent longitudinal movement of the removable members, a clamping chair adapted for clamping engagement with said body and the web of a 90 railway rail to attach the said body to the rail.
8. In a re-railer, the combination with a rail road trackway of a member adapted to be detachably mounted upon the outside of 100 one of the rails of said rail road track, said member overlying the ball of the rail and having grooves upon said overlying portion to guide the flange of a wheel, and a second member adapted to be detachably 105 mounted upon the inside of the rail opposite the first mentioned rail, the top of the second member adjacent the ball of the rail terminating below the top of the ball of said rail.

JAKOB PODIEN.
